ALL PURPOSE GARMENT HANGER

Arthur D. Reed and Arthur W. Nonn,
Jackson, Mich.

Application February 12, 1944, Serial No. 522,130

2 Claims. (Cl. 223—87)

This invention relates to a garment hanger and it is one object of the invention to provide a garment hanger of such formation that it may be used for holding men's or women's clothing, the hanger being of such formation that when coats, trousers, dresses, belts or other apparel are applied to the hanger they will be kept smooth being free from wrinkles and neat in appearance when removed from the hanger.

Another object of the invention is to provide a hanger wherein a portion for carrying trousers or a lady's skirt is of such shape that by inverting the hanger it may accommodate itself to an evening dress or other sleeveless garment.

Another object of the invention is to provide the hanger with a suspending hook adapted to be readily transferred from one position in which the hanger is adapted for holding men's coats to another position in which the hanger will be inverted and adapted to hold women's sleeveless garments.

Another object of the invention is to form the hanger that the hook may be very easily applied to it and firmly held in its proper position after being applied, the hook being also easily removable when it is desired to invert the hanger and again apply the hook to it.

Another object of the invention is to provide a hanger which can be stamped from cardboard, fiber composition, or other sheet material in a single operation and thus cheaply manufactured.

The invention is illustrated in the accompanying drawing wherein:

Figure 1 is a front view of the improved hanger, the hook being so applied to the hanger that it is adapted to hold a man's coat and trousers.

Figure 2 is a view looking from the right of Figure 1.

This improved garment hanger is preferably formed from stiff cardboard or fiber composition and has a body 1 formed with diagonally cut edges 2 extending from opposite sides of an extension or neck 3 at such an angle that the arms 4 of the hanger will conform to the slope of the shoulders of a man's coat when a coat is placed on the hanger. Ends of the arms 4 have arcuate edges 5 merging into the inwardly presented arcuate edge portions 6 of a cross bar 7 which is formed integral with ends of the arms 4 and has a straight cut upper edge 8 merging into lower edges of slits 9 which extend longitudinally of the cross bar and terminate in enlarged and upwardly projecting circular openings or terminals 10. The arcuate edge portions 6 of the cross bar merge into the arcuate edge 11 of an

extension or neck 12 formed midway the length of the cross bar 7 and midway the length of the cross bar there has been formed a slot 13 disposed in spaced parallel relation to the edge 8 of the cross bar and having an entrance throat 14 midway its length. This throat leads from the upper edge of the cross bar and has arcuate side edges 15 merging into edges of the slot and the cross bar in order that a belt or the like may be easily moved into the slot when applied to the hanger.

Between inner ends of the slots 9 the body 1 has an upwardly bowed lower edge 16 constituting the upper edge of a large opening 17 and merging into upper edges of the slots 9 as shown at 18. Elongated openings or slots 19 and 20 are formed in the extensions or necks 3 and 12 and reinforced at their inner ends by discs 21 of fabric or tough paper and in alignment with outer ends of the slots 19 and 20 the extremities of the necks are formed with notches or recesses 22 and 23. The hook 24 by means of which the hanger is to be suspended from an overhead support is formed of resilient wire and has its shank 25 bent upwardly back upon itself to form a bill 26 terminating in a rolled end 27 and of a length adapting the bill to be passed through the slot 19 or slot 20 and have its rolled end engaged in the notch 22 or notch 23. By this arrangement the hook may be easily applied to the hanger and since the rolled end of the bill is engaged in a notch the hook will be prevented from slipping out of engagement with the hanger and the hanger will be prevented from tilting out of a horizontal position.

When this hanger is in use the hook is disposed as shown and a coat applied to the hanger with the arms 4 of the hanger engaging under the shoulders of the coat and the neck opening of the coat. The fact that the arms have diagonally extending upper edges causes the arms to conform to the slope of the shoulders of the coat and since the roller end of the bill of the hook engages in the notch 22 the hanger will be prevented from tilting upon the bill of the hook to a position in which one side of the hanger sags and causes the coat to lose its shape and become wrinkled. Trousers may also be applied to the hanger by folding them and then passing the trousers through opening 17 and suspending them across the upper edge of the cross bar 7. Side portions of the trousers or portions of the waist band of a woman's skirt may be engaged in the slots 9 to prevent the garment from slipping and falling off the hanger and a neck tie or a woman's belt

may be passed through the mouth 14 into the slot 13 and suspended from the hanger. When a woman's evening gown or other sleeveless dress is to be applied to the hanger, the hook 24 is removed from the opening 19 and the hanger then inverted and the hook passed through slot 20 with the rolled end of its bill engaged in the notch 23. The hanger will then be suspended from the hook with the neck 12 and the cross bar 7 uppermost. The hanger may then be slipped into the upper portion of the garment and since the garment will rest upon the curved edges 6 of the cross bar, it will remain in its proper position upon the hanger and not distorted by slipping out of place.

Having thus described the invention, what is claimed is:

1. A garment hanger comprising a body having a neck and arms extending from opposite sides of the neck at a downward incline, a cross bar under said body extending longitudinally thereof and having its ends integrally united to ends of said arms, said cross bar having a depending neck midway its length and at opposite sides of its neck having upwardly bowed curved lower edge portions merging into the edge of the neck and ends of the body, the upper edge of said cross bar being straight and spaced from the body by an opening having its ends terminating in horizontal slits between ends of the arms and the cross bar, there being provided at the center of the cross bar a longitudinal slot spaced from the upper edge

of the cross bar and formed midway its length with a mouth opening through the upper edge of the cross bar, said necks being each formed with a vertical slot and a notch at the free end of the neck aligned with the slot in the neck, and a hook having a shank bent back upon itself to form a bill passed through the slot of a selected neck and terminating in a rolled end engaged in the notch of the neck to firmly and removably hold the hook in engagement with the neck.

2. A garment hanger formed from a blank of sheet material and having a body and a cross bar, the blank having its intermediate portion cut out to provide an opening between the body and the cross bar, said body having a neck midway its width and arms extending from opposite sides of the neck, said cross bar also having a neck midway its width and a horizontal upper edge spaced from the body by the opening of the blank and by slits constituting extensions of the said opening, each neck being formed with a vertical slot midway its width and with a notch in its outer end aligned with its slot, and a hook for suspending the hanger from a support formed of resilient wire and having its shank bent back upon itself to form a bill passed through the slot of a selected neck and terminating in a latch for engaging in the notch of the neck and removably holding the hook in engagement therewith.
